CLAIM

We claim the ornamental design for a lure, as shown and described.

DESCRIPTION

FIG. 1 is a perspective view of a first embodiment of a lure; FIG. 2 is a right side elevation view of the first embodiment of the lure, the left side elevation view of the first embodiment of the lure being a mirror image thereof; FIG. 3 is a top plan view of the of the first embodiment of the lure; FIG. 4 is a rear elevation view of the first embodiment of the lure; FIG. 5 is a front elevation view of the first embodiment of the lure; FIG. 6 is a bottom plan view of the first embodiment of the lure; FIG. 7 is a perspective view of a second embodiment of a lure; FIG. 8 is a right side elevation view of the second embodiment of the lure, the left side elevation view of the second embodiment of the lure being a mirror image thereof; FIG. 9 is a top plan view of the of the second embodiment of the lure; FIG. 10 is a rear elevation view of the second embodiment of the lure; FIG. 11 is a front elevation view of the second embodiment of the lure; FIG. 12 is a bottom plan view of the second embodiment of the lure; FIG. 13 is a perspective view of a third embodiment of a lure;

(Continued)

FIG. 14 is a right side elevation view of the third embodiment of the lure, the left side elevation view of the third embodiment of the lure being a mirror image thereof;
FIG. 15 is a top plan view of the of the third embodiment of the lure;
FIG. 16 is a rear elevation view of the third embodiment of the lure;
FIG. 17 is a front elevation view of the third embodiment of the lure;
FIG. 18 is a bottom plan view of the third embodiment of the lure;
FIG. 19 is a perspective view of a fourth embodiment of a lure;
FIG. 20 is a right side elevation view of the fourth embodiment of the lure, the left side elevation view of the fourth embodiment of the lure being a mirror image thereof;
FIG. 21 is a top plan view of the of the fourth embodiment of the lure;
FIG. 22 is a rear elevation view of the fourth embodiment of the lure;
FIG. 23 is a front elevation view of the fourth embodiment of the lure; and,
FIG. 24 is a bottom plan view of the fourth embodiment of the lure.
The broken line showing of portions of the lure are included for the purpose of illustrating only and form no part of the claimed design.
